UNITED STATES PATENT OFFICE.

CHARLES LEWIS BESSONETT, OF TEMPLE, ASSIGNOR TO THE BESSONETTE COTTON COMPRESS MANUFACTURING COMPANY, OF WACO, TEXAS.

COTTON-BALING MACHINE.

SPECIFICATION forming part of Letters Patent No. 530,000, dated November 27, 1894.

Application filed January 31, 1894. Serial No. 498,589. (No model.)

To all whom it may concern:

Be it known that I, CHARLES LEWIS BESSONETT, a citizen of the United States, residing at Temple, in the county of Bell and State of Texas, have invented a new and useful Cotton-Compress, of which the following is a specification.

My invention relates to improvements in cotton-compresses; and has particular reference to that class thereof wherein the cotton is compressed between two pressure-rolls the same acting upon an intermediate core-roll.

The objects of my invention are to improve the general mechanism of this class of compresses and especially to improve the mode of applying pressure to the pressure rolls, and to improve the manner of mounting the core-roll in position within the compress, and for facilitating the removal of said core-roll; and the elevation therefrom of the compress-roll.

Other objects and advantages of the invention will appear in the following description, and the novel features thereof will be particularly pointed out in the claims.

Referring to the drawings:—Fig. 1 is a side view of a machine embodying my invention. Fig. 2 is a rear view of the same. Fig. 3 is a plan view of the cylinders, crank, and connecting pipes, showing the upper portion of the framework. Fig. 4 is a detail horizontal section, taken parallel with and in the plane of the axis of the core roll. Fig. 5 is a detail side view of the mechanism for removing the core roll. Fig. 6 is a detail front view of the same.

Like numerals of reference indicate like parts in all the figures of the drawings.

Upon a suitable stable base comprising transverse and longitudinal sills 1 and 2 respectively, I bolt a pair of opposite vertical frames or standards 3, the same terminating at their lower ends in feet, perforated for the reception of the bolts. These frames or standards are preferably formed of angle-iron, and are provided near their lower ends with transverse journal boxes 4, in which there is journaled loosely a transverse shaft 5 that has mounted thereon and designed to revolve therewith a lower compressing-roller 6. The shaft has its ends extended beyond

its bearings and has mounted thereon spur-gear-wheels 7, whose pitch-diameters are preferably about the same as the diameter of the roll 6.

Formed in the standards or frames 3 at a point above the bearings 4 are vertical slots 8, and arranged in said slots are journal-boxes 9 that are flanged and adapted for vertical movement within the slots. These journal boxes 9 carry a transverse shaft 10, which between its bearings has rigidly mounted thereon a compressing-roll 11. The ends of the shaft 10 project beyond their bearings like those of the shaft 5, and are provided with rigidly mounted spur-gears 12, whose pitch-diameters are the same as those of the gears 7.

Between the gears 7 and 12 there are interposed opposite similar spur-gears 13 that intermesh therewith, and in each gear 13 there is arranged a transverse shaft or axle 14. Arranged upon these shafts or axles 14 at opposite sides of each gear 13 are collars 15, and connected to these collars 15 are the inner ends of opposite pairs of connecting-arms 16 whose outer ends are connected respectively to the shafts 5 and 10 at opposite sides of the gears 12.

Arranged in the slots 8 of the frames or standards 3, between the rolls 6 and 11, are journal-boxes 17, whose inner ends are flanged at 18 to embrace the edges of the slots. In one of these boxes there is journaled for loose rotation a core-shaft 19, the same being preferably hollow, and in the other there is located for reciprocal movement a bolt 20 having at its inner end a bearing-pin 21. Immediately in rear of the inner end, the bolt 20 is provided with an annular groove 22, and arranged upon said end and perforated to agree with the groove 22 is a flange-plate 23. Screws 24 are passed through the perforations in the flange-plate and engage the groove 22. This flange-plate is bolted to a circular head or disk 25 against which the end of the bolt 20 abuts and through which the bearing-pin 21 passes, and is designed to form one of the bearings for the core-shaft 19. The disk 25 serves as a header at one end of the shaft 19 when in place and corresponds with a similar heading-disk at the opposite end of the shaft to hold the edges of the sheet of cotton

flush during the winding operation. A yoke-plate 26 is, by means of bolts 27, secured to the outer face of the bearing-block 17 that supports the bolt 20, and the said yoke-plate is provided with a series of aligning bearing-flanges 28 in which is arranged for rotation a shaft 29, which terminates at one end in an operating crank-handle 30. Between those bearing-flanges 28 that are at opposite sides of the outer end of the bolt 20 the shaft 29 is provided with a cranked-portion 31 that loosely passes through an opening 32 formed transversely in the bolt 20.

The crank-handle 30 is provided with a pair of bearing-ears 33, between which there is intermediately pivoted a finger-lever 34, whose free end is normally pressed upward from the crank-handle by the spring 35. The inner end of the lever is pivoted at 36 to a locking-rod 37 that passes loosely through a perforation in a collar 38 located on the shaft 29 and may be engaged with any one of a series of perforations 40 formed in the end flange 28.

In order to remove the core-roll it will be obvious from the foregoing that it is simply necessary to compress the lever 34 by the finger or thumb so as to withdraw the locking-bolt or rod 37 from the socket or opening with which it may be engaged in the flange 28. After this has been done the crank is partially revolved and with it revolves the shaft 29, which by reason of its cranked-portion 31 withdraws the bolt 20 and the bearing-pin 35 from the end of the hollow core-shaft 19, and thus permits the opposite end of said shaft to be disengaged from the box and the core-shaft together with the bale of cotton contained thereon removed. A reversal of this operation of course will cause a locking of the shaft in position.

Extending upward from the upper box 9 is a pair of vertical rack-bars 41 arranged at the outer sides of the frames or standards 3; and journaled in transverse bearings 42 arranged upon the upper ends of said frames or standards is a transverse shaft 43, at whose ends are located small pinions 44, which engage with the aforesaid rack-bars 41, and consequently prevent any independent movement of the rack-bars or any uneven movement of the compressing-roll.

Bolted to the upper ends of the opposite frames or standards 3 is a pair of opposite cylinders 45, and located in each cylinder is a piston-head 46, at whose under-side there is secured a piston-rod 47 that passes down through the lower head of the cylinder, the upper heads of the cylinders being closed. The lower ends of the piston-rods 47 are pivotally connected at 48 to cross-heads 49, which are bolted securely at 50 to the backs of the rack-bars 41. The upper and lower ends of the cylinders are connected by upper and lower intermediate pipes 51 and 52 respectively, whereby communication between the cylinders is established above and below the

piston-head, and the upper pipe is provided with an air-chamber 53 about midway its length. At one side of the air-chamber 53 and between the pipes 51 and 52 there is located a three-way valve or cock 54, whose plug 55 extends without the valve-casing and is journaled in a bearing 56 formed in the adjacent cylinder 45. A pulley 57 is arranged rigidly on the valve-stem, and through the medium of cords 58 may be rotated to operate the stem. From one branch of the valve 54 there leads a pipe 59 that communicates with the upper pipe 51 and with a safety-valve 60 interposed between the pipes 59 and 51. The lower branch of the valve-casing 54 is connected by a pipe 61 to the lower pipe 52, and a feed-pipe 62 leads to any suitable pump. Not shown. An overflow-pipe 63 leads horizontally from the pipe 51 to the bottom of a receiving-tank 64, and an overflow-pipe 65 leads from the upper end of said tank to a well or other waste-water receptacle.

The object of the construction thus described is to maintain an evenness of pressure upon the ends of the roll 11 and to provide for a convenient elevation of the roll when it is desired to insert or remove the core-roll.

In order to elevate the roll 11 the three-way valve is so manipulated as to permit the water under pressure from a pump to flow into the bottoms of the cylinders through the pipes 61 and 52, which of course acting under the piston-heads 46 elevates the latter and with them the rack-bars and roll 11. When it is desired to lower the roll the valve is manipulated so as to throw the pipes 52, 61, 59 and 51 into communication and close the supply-pipe and the weight of the roll will cause the water to be forced from the bottoms of the cylinders to the tops at points above the piston heads. The valve being opened any desired pressure of water may be exerted upon the piston-heads, and consequently upon the roll 11. The valve is then closed so as to cut off the supply from the pump and the machine started or set in operation. As the cotton accumulates upon the core-roll and consequently the bale increased in size the roll 11 is elevated and the pistons moved upward against the body of water contained between the pistons and the upper ends of the cylinders. The safety-valve is set to withstand a certain pressure, and when it has been reached the water escapes therefrom into the pipe 63 and tank 64 and is conducted from the latter back to the source of supply or any other point.

The frames 3 are provided with forwardly disposed branches, in which are journaled upper and lower shafts 66 and 67 respectively. The shaft 66 carries a pair of outer spur-gears 68 and inner smaller spur-gears 69, which engage with the gears 7. The shaft 67 carries at its ends small pinions 70, which engage with the large gears 68. The said shaft also carries a pulley 71, which is driven by a belt 72 leading from any suitable motor.

Arranged in front of the machine thus described is a wire-gauze cylinder 73; which it will be seen is journaled upon an axis 74, and contained within the casing 75 and having a semicircular roof. The casing leads to a chute, which delivers the cotton in a bat between the core and lower rolls, and its opposite end is connected by a flue 76 with the gin.

It will be seen that rotation is given to the several gears primarily from the shaft 67, where the power is multiplied by delivering it to a larger gear 68, to its shaft 66, to a smaller gear 69 on said shaft, and thence to a train of gearing 7, 13 and 12.

The arrangement of the bearing-boxes of the pressure roll shaft 10 in vertical slots above the plane of the core-roll, the intermediate gear 13 meshing with the gears on said pressure roll shaft 10 and the lower shaft 5, and the pivotal arms 16 connecting said intermediate gear with the upper and lower shafts 10 and 5, causes a downward pressure upon the core roll, which is in addition to the pressure produced by the hydraulic means above described. In this way the weight of these parts is utilized to assist in the compressing operation.

From the foregoing description in connection with the accompanying drawings, it will be seen that I have provided an improved construction of press of the class designated, wherein the pressure upon the cotton upon the core-roll may be regulated and is even throughout the length of said roll, that the bale will be evenly formed by reason of the presence of the revolving disk 25 against which the cotton is headed; that I have provided a convenient means for raising the pressure-roll from the core-roll when desired; and, furthermore, for locking in a suitable position for operation the core-roll.

I do not limit my invention to the precise details of construction herein shown and described, but hold that I may vary the same to any degree and extent within the knowledge of the skilled mechanic.

Having described my invention, what I claim is—

1. In a cotton-compress of the class described, the combination with the movable core roll, of a movable shaft and a pressure roll mounted on said shaft and means for driving the same, rack-bars extending from said shaft, pinions gearing in said rack-bars, and rigidly attached to each other whereby uniform motion of the opposite rack bars is obtained, hydraulic cylinders, pistons in the cylinders with piston rods connected to said rack-bars, and means for admitting fluid under pressure to either side of the said pistons, substantially as described.

2. In a cotton-compress of the class described, the combination with the opposite slotted frames, and the core-roll arranged movably in the slots, of a movable shaft, a pressure roll mounted thereon, and means for driving the same, rack-bars extending from

said shaft, pinions gearing in said rack-bars, and rigidly attached to each other whereby uniform motion of the opposite rack bars is obtained, hydraulic cylinders, pistons mounted in the said cylinders, and piston rods connected with the rack bars, and means for admitting water under pressure at opposite sides of the pistons, substantially as described.

3. In a cotton-compress of the class described, the combination with the movable core roll, of a movable shaft and a pressure roll mounted on said shaft and means for driving the same, rack-bars extending from said shaft, pinions gearing in said rack-bars, and rigidly attached to each other whereby uniform motion of the opposite rack bars is obtained, hydraulic cylinders, pistons in the cylinders with piston rods connected to said rack bars, the upper and lower connecting pipes 51 and 52, the safety valve 60, the three-way cock 54, and the pipes 59 and 61, substantially as described.

4. In a cotton-compress of the class described, the combination with the opposite slotted frames, and the core roll arranged movably in the slots, of a movable shaft, a pressure roll mounted thereon, and means for driving the same, rack-bars extending from said shaft, pinions gearing in said rack-bars, and rigidly attached to each other whereby uniform motion of the opposite rack bars is obtained, hydraulic cylinders, pistons mounted in the said cylinders, piston rods connected with the rack bars, the upper and lower connecting pipes 51 and 52, the safety valve 60, the three-way cock 54, and pipes 59 and 61, substantially as described.

5. In a cotton-compress of the class described, the combination with a movable core roll, of a movable shaft, a pressure roll mounted on said shaft, hydraulic cylinders, pistons in the said cylinders with piston rods bearing on the said shaft, the upper and lower connection pipes 51 and 52, the safety valve 60, the three-way cock 54, the pipes 59 and 61, the overflow pipe 63 extending from the safety valve 60, the tank connected to the lower end of the pipe 63, and the return pipe 65, substantially as described.

6. In a cotton-compress of the class described, the combination with the movable core roll, of a movable shaft and a pressure roll mounted on said shaft and means for driving the same, rack-bars extending from said shaft, pinions gearing in said rack bars, hydraulic cylinders, pistons in the cylinders with piston rods connected to said rack-bars, the upper and lower connection pipes 51 and 52, the safety valve 60, the three-way cock 54, the pipes 59 and 61, the overflow pipe 63 extending from the safety valve 60, the tank 64 connected to the lower end of the pipe 63, and the return pipe 65, substantially as described.

7. In a cotton-compress of the class described, the combination with the opposite

slotted frames, and the core-roll arranged movably in the slots, of a movable shaft, a pressure roll mounted thereon, and means for driving the same, rack-bars extending from said shaft, pinions gearing in said rack-bars, hydraulic cylinders, pistons mounted in the said cylinders, and piston rods connected with the rack bars, upper and lower connection pipes 51 and 52, the safety valve 60, the three-way cock 54, the pipes 59 and 61, the overflow pipe 63 extending from the safety-valve 60, the tank connected to the lower end of the pipe 63, and the return pipe 65, substantially as described.

15 8. In a cotton-compress of the class described, the combination with the opposite frames having guides therein, and compressing rollers, mounted in said frames, of opposite sliding boxes for the core roll mounted in said guides, a core-shaft removably arranged in one of said boxes and terminating short of the opposite box, a reciprocating bolt terminating at its inner end in a bearing-pin arranged in the opposite box, and adapted to engage removably with the core-roll, a transverse shaft supported in bearings at the side of the frame and having end and intermediate cranks, means for locking the shaft, there being a loose connection between the intermediate crank thereof and the outer end of the bolt, substantially as described.

9. In a cotton-compress of the class described, the combination with the opposite frames, and the upper and lower compressing rollers, said frames having slots, of opposite sliding boxes located in the slots, a core-shaft removably arranged in one of said boxes and terminating short of the opposite box, said shaft having a heading disk, a reciprocating bolt terminating at its inner end in a bearing-pin arranged in the opposite box and adapted to engage removably with the core-roll, means for reciprocating said bolt, and a heading-disk carried by the bolt to correspond with that on the shaft substantially as specified.

45 10. In a cotton-compress of the class described, the combination with the opposite frames, and the upper and lower compressing rollers, said frames having slots, of opposite sliding boxes located in the slots, a core shaft removably arranged in one of said boxes and terminating short of the opposite box, a reciprocating bolt terminating at its inner end in a bearing pin arranged in the opposite box and adapted to engage removably with the core-roller, a transverse shaft supported in bearings at the side of the frame and having end and intermediate cranks, means for locking the shaft, there being a loose connection between the intermediate crank thereof and the outer end of the bolt, substantially as specified.

11. In a cotton-compress, the combination with the opposite slotted frames, the upper and lower compressing rollers, the boxes arranged in the slots, and the core-shaft ar-

ranged removably in one of the boxes and terminating short of the opposite box, of the reciprocating bolt located in said opposite box and having an opening at its outer end, 70 and a bearing-pin at its inner end and grooved in rear of the latter, a flanged plate arranged on the inner end of the bolt and perforated to agree with the groove, pins extending from the perforations into the groove, a disk loosely mounted on the bearing pin and bolted to the flange-plate, a transverse cranked shaft, means for locking said shaft, and connections between the bolt and the crank of the shaft, substantially as described.

12. In a cotton-compress, the combination with opposite slotted frames, upper and lower compressing rollers, bearing-boxes arranged in the slots of the frames and a core-shaft arranged removably in one of the boxes and 85 terminating short of the opposite box, of a reciprocating bolt located in said opposite box and carrying a terminal-bearing pin to engage a socket in the adjacent end of the core-shaft, said bolt being provided in its outer end with 90 a transverse perforation, a transverse yoke-bar carried by the outer end of the box in which said bolt is mounted and having guide flanges provided with bearings, a shaft having an intermediate crank engaging the perforation in the outer end of the bolt, a crank handle for operating the shaft and provided with bearings at its outer side, a thumb-lever pivoted between the bearings, and a locking rod connected to the inner end of the thumb-lever and adapted to engage one of a series of openings formed in the yoke-bar, substantially as described.

13. In a device for detaching the core roll shaft, in a cotton compress, the combination 105 with journal boxes for the ends of the shaft, of the core-shaft arranged removably in one of the boxes and terminating short of the opposite box, the reciprocating bolt located in said opposite box and having an opening at 110 its outer end, and a bearing-pin at its inner end and grooved in rear of the latter, a flanged plate arranged on the inner end of the bolt and perforated to agree with the groove, pins extending from the perforations into the 115 groove, a disk loosely mounted on the bearing pin and bolted to the flanged plate, a transverse cranked shaft, means for locking said shaft, and connections between the bolt and the crank of the shaft, substantially as described.

14. In a device for detaching the core roll shaft in a cotton compress, the combination with journal boxes for the ends of the shaft, of the core-shaft arranged removably in one 125 of the boxes and terminating short of the opposite box, a reciprocating bolt located in said opposite box and carrying a terminal-bearing pin to engage a socket in the adjacent end of the core-shaft, said bolt being provided in its outer end with a transverse perforation, a transverse yoke-bar carried by the outer end

of the box in which said bolt is mounted and having aligning flanges provided with bearings, a shaft having an intermediate crank engaging the perforation in the outer end of 5 the bolt, a crank handle for operating the shaft and provided with bearings at its outer side, a thumb-lever pivoted between the bearings, and a locking-rod connected to the inner end of the thumb lever and adapted to engage

one of a series of openings formed in the yoke- to bar, substantially as described.

In testimony that I claim the foregoing as my own I have hereto affixed my signature in the presence of two witnesses.

CHARLES LEWIS BESSONETT.
